UNITED STATES PATENT OFFICE.

INEZ EMERY FITZ GERALD, OF OAKLAND, CALIFORNIA.

CLOTHES-HOLDER.

1,272,244.

Specification of Letters Patent.

Patented July 9, 1918.

Application filed November 1, 1915. Serial No. 59,027.

To all whom it may concern:

Be it known that I, INEZ EMERY FITZ GERALD, a citizen of the United States, residing at Oakland, in the county of Alameda and State of California, have invented certain new and useful Improvements in Clothes-Holders, of which the following is a specification.

This invention relates to improvements in 10 devices for maintaining clothes in the wash boiler below the level of the water.

The principal object of my invention is to provide a simple effective device for the above-mentioned purpose such as may be 15 readily attached to any wash boiler, and which is easily removed therefrom and which effectively holds the clothes below the surface of the water.

With these and other objects in view my 20 invention consists in the novel construction, combination and arrangement of parts herein illustrated and more specifically pointed out in the appended claims.

Reference being had to the accompanying 25 drawing forming a part of this specification,

Figure 1 is a view in plan of one form of my improved clothes holder.

Fig. 2 is a view in section through a wash 30 boiler showing my improved device positioned therein.

Fig. 3 is a view in plan of a modified form of the holder.

Fig. 4 is a view in section through a wash 35 boiler showing this form of device positioned therein.

Referring to corresponding parts by the same numerals of reference, 1 denotes the wash boiler having the beaded top edge 2, 40 and as shown in Fig. 1, my improved device consists of a ring 3, covered with a wire screen 4, having certain holding clips 5. These clips are provided with lower loop portions receiving the ring 3, and the upper 45 edge is curved as shown at 6 to provide a contracted resilient throat, which is spread apart when the upper end of the clip is sprung over the head 2 so that it requires considerable effort to remove it therefrom. 50 Thus when in use the ring is placed in the wash boiler and the devices 5 positioned over the head of the boiler, thereby holding the ring and attached wire screen against upward pressure of the clothes, and permit-

ting a limited vertical movement of the 55 screen relative to the clips.

In the form shown in Figs. 3 and 4, the ring 3' is provided with the opening 7 and the ends of the wire are at this point bent upwardly as shown at 8 and provided with 60 loops 9, which serves as a handle to contract the ring for the purpose hereinafter described.

In this form the wire screen 10 is provided, the edge of the wire being bent downwardly as shown at 11 before connecting to the ring, and adjacent the opening 7 the ends of the screen are cut off short and not fastened to the ring. By connecting the screen to the ring in this manner the ring is 70 permitted to contract by pressure on the handles 9. This type is intended to be used in the boiler having a bead 12 around the surface thereof. The screen is inserted and removed by squeezing together the handles 75 9 contracting the ring 3' a sufficient amount to allow the ring to enter this bead, where it springs into position and is thus held against the upward pressure of the clothes.

It will thus be seen that I have provided 80 a simple and effective means for holding the clothes in the boiler below the surface of the water, and while I have shown the preferred embodiment of my invention it will be understood that minor changes may be made in 85 detail and design within the scope of the claims.

Having thus described my invention I claim as new and wish to cover by Letters Patent:

1. A clothes holder of the character described comprising a ring having wire mesh attached thereto, and clips having resilient portions to engage a receptacle to support said ring, said clips and ring being so connected as to provide for a limited relative movement at the point of connection.

2. A clothes holder of the character described comprising a ring having wire mesh attached thereto, and clips having resilient 100 portions shaped to engage the edge of a receptacle, said clips being also provided with lower loop portions receiving the ring and shaped to permit of a limited vertical movement of said ring.

In testimony whereof I affix my signature.

INEZ EMERY FITZ GERALD.
